UNITED STATES PATENT OFFICE.

CLAUDE M. TREADWELL, OF LONDON, ENGLAND, ASSIGNOR OF ONE-HALF TO CHARLES BAUER, OF LONDON, ENGLAND.

DEVICE FOR PRACTISING GOLF-PUTTING.

1,076,722.

Specification of Letters Patent.

Patented Oct. 28, 1913.

Application filed October 6, 1911. Serial No. 353,294.

To all whom it may concern:

Be it known that I, CLAUDE MALLAM TREADWELL, a subject of the King of Great Britain, residing at Forest Hill, London, England, have invented new and useful Improvements in or Relating to Devices for Practising Golf Putting, of which the following is a specification.

This invention has reference to an improved device for use in practising golf putting and the object of my invention is to provide an improved trap or putting "disk" for the ball which will very slightly if at all retard or otherwise interfere with the travel of the ball even when traveling slowly to the hole so that substantially the same strength of putt will hole the ball when my improved trap or putting disk is used as would be required if the ball were being putted on a putting green. The trap or putting disk should be so made that while it retains a ball putted with proper strength or firmness it will permit a ball to again leave the hole if the putt made has been too firm or strong.

Figure 1 of the drawing is a perspective view of the flexible, resilient putting disk embodying my present invention; Fig. 2 is a similar view of the disk, but with a ball shown as resting on or passing over the side of the disk, showing the latter as deflected or flattened down by the weight of the ball; Fig. 3 is a perspective view partially in section showing a putting disk embodying my invention but having a reinforced edge; Fig. 4 is a similar view showing a putting disk made of two plies or thicknesses; Fig. 5 is a perspective view partially in section of a putting disk embodying my invention, but having means for anchoring it in place.

My improved trap or putting disk is made of pliable and resilient fabric or material made into the form most advantageously of a truncated hollow cone, as shown at A, Figs. 1 and 2—although I do not wish to restrict myself thereto—and which material will be depressed, see Fig. 2, by the pressure thereon due to the weight of the ball C as the latter passes thereover to the "hole" and which will recover its original form so soon as the ball has passed from off it. The fabric or material should further be of such a nature that while comparatively little or almost no resistance will be offered to the travel of the ball when the latter is travel-

ing toward the hole of the trap or disk it will offer substantial resistance to the movement of the ball horizontally or substantially as from out of the hole. The base of the trap may be left open or the trap or putting disk may be provided with a bottom, as B, Figs. 1 and 2, on which the ball will rest when "holed out" as by this means the disk will be prevented in a large measure from moving when the ball strikes the back of the hole.

If desired my improved trap or putting disk may be provided with means, for example, lugs or equivalents to receive pins or the like whereby it may be secured *in situ* and if desired the edge of the "hole" may be strengthened or reinforced to enable it the better to withstand the impact of the ball against the back of the hole.

In Fig. 5 I have shown an embodiment of my invention wherein the putting disk is provided with the lugs or cross bars h having an opening in which a pin i may be received for anchoring the disk in place. In Fig. 3 I have shown the edge of the "hole" as reinforced by the strip a.

I have found that paper is a very suitable material of which to make my improved flexible trap or putting disk although I do not in any way intend to limit myself with regard to the material I may employ, for example, rubber, parchment, hair cloth, buckram, wire cloth, or thin celluloid are probably only some of the materials which might be employed, and if such or any other material does not of itself possess the necessary qualities of pliability and elasticity it may be made to do so. For example thin celluloid or comparatively stiff material may be made more pliable and yet retain sufficient elasticity by forming it with slits, cuts, perforations or apertures, these being made to be sufficiently close together to avoid the formation of such ruts or ridges as would seriously disturb or interfere with the travel of the ball.

If desired the trap or disk may be made up of two or more thicknesses or layers of a single or several materials. In Fig. 4 I have shown an embodiment of my invention wherein the two layers or thicknesses of the putting disk are designated by e and f, respectively. The edge of the "hole" in this embodiment may also be reinforced as shown in Fig. 3 if desired.

If made in the form of a truncated hollow cone, as herein illustrated, the depth of the trap or disk will be about equal to or a little less than one-half the diameter of the ball, although I do not restrict myself thereto as the proper dimensions depend on the particular material or materials of which the trap or disk is made. The dimensions otherwise of the disk will also depend upon the material and the particular taste of the user, for example the outside diameter of the base will be greater accordingly as the material of which the disk is made is stiffer and the diameter of the hole will be smaller accordingly as the user desires to set himself a more difficult task. I have used putting disks made in accordance with my invention, having the following dimensions:—diameter of disk 8 $\frac{1}{2}$ inches; diameter of the hole 4 inches; height of the inner edge of disk $\frac{3}{8}$ of an inch from the “green” or base, but I do not wish or intend to confine myself to these. It will be seen that the diameter of the disk is large compared to the height thereof, and as a result the walls or sides of the putting disk have a general slope upward. This is important because it is very desirable that the walls of the disk should not present an appreciable resistance to the movement of the golf ball thereover.

If the material is not of itself waterproof or damp resistant it may be rendered to be so by any suitable known process care being exercised that no waterproofing process be employed which would seriously interfere or disturb the flexibility of the trap or disk.

The trap or disk may be coated with enamel, paint or other material or with fabric to increase or alternatively decrease its grip on the ball or to increase or alternatively decrease its flexibility or pliability

and the said disk according to the material employed in its manufacture may be made 45 by molding, stamping or otherwise.

What I claim as my invention and desire to secure by Letters Patent is:—

1. A putting disk for use in the practice of golf having a hollow truncated cone 50 shape and made of thin very pliable but resilient material, the sides of the disk having insufficient rigidity to support the golf ball whereby when a golf ball rolls onto said disk the portion thereof over which the ball passes will be depressed by the weight of the ball and lie flat on the ground, the resiliency of the walls causing the disk to resume its normal shape as soon as the ball has passed off therefrom. 60

2. A putting disk having the shape of a hollow truncated cone with the base thereof of large diameter compared with the height, said disk being made of very pliable but resilient material whereby the disk will 65 yield to the ground under the weight of a golf ball and will resume its normal shape after the ball passes off therefrom.

3. A putting disk of thin, pliable but resilient material having a central golf-ball- 70 receiving aperture and inclined sides, the material of the disk having sufficient pliability to yield readily under the weight of a golf ball without presenting any appreciable resistance to the passage of the ball, 75 the resiliency of the material causing the disk to assume its normal shape after the ball passes thereover.

In testimony whereof I have signed my name to this specification in the presence of 80 two subscribing witnesses.

CLAUDE M. TREADWELL.
